LIFEBOAT FASTENING MEANS

Peter Full, Vermillion, Ohio

Application November 17, 1944, Serial No. 563,818

3 Claims. (Cl. 9—46)

1

This invention relates to means for mounting and releasably securing life boats on the decks of ships.

The primary object of the invention is the provision of a fastening means of the character described, which is simple and efficient in its construction, is easily operable to engage or release a boat, and cooperates with the support or mounting means for a boat to hold it in rigid relation to the deck.

A further object of the invention is the provision of a gunwale clamp as well as a keel clamp for a boat, which are interconnected and operable in conjunction to simultaneously clamp or release the gunwale and keel whereby to securely hold the boat against any movement relative to the deck on which it is mounted.

This application is filed as a continuation in part of my co-pending application Serial No. 518,502, filed January 17, 1944, which became abandoned June 12, 1946.

The invention is fully described in the following specification, and a preferred embodiment thereof illustrated in the accompanying drawings, in which—

Figure 1 is a plan view of a life boat davit mounted on the deck of a ship fragmentarily shown and including the clamping means embodying the invention with a boat firmly held thereby in rigid relation to the deck, and also showing in dotted lines the boat swung out in lowering position; Fig. 2 is a side elevation of a life boat and the mounting and securing means shown in Fig. 1; Fig. 3 is an enlarged fragmentary section on the line 3—3 in Fig. 1, with parts broken away; Fig. 4 is a similar view more in sectional detail with the clamping means released from the boat and the boat in slightly spaced relation from the support; Fig. 5 is an end view of Fig. 1, showing the manner of raising and lowering the boat; Fig. 6 is a similar view with the boat completely lowered in the water and the carrying hooks of the davit released therefrom; Fig. 7 is a side view of an end portion of the davit and boat as shown in Fig. 5, and Fig. 8 is an end view of a boat lowering arm of the davit with the supporting hook released from the boat in the relative positions shown in Fig. 6.

Referring to the drawings, A designates a boat deck and B a life boat for mounting thereon. The davit means shown for raising and lowering the boat with respect to the deck comprises two standards 1, 1, spaced lengthwise of the deck, and each having a vertically swinging arm 2 associated therewith at its outer or water side 55

2

and pivoted at its lower end adjacent to the lower end of the standard, as at 3, whereby the arm may be disposed in upright position as shown in Fig. 5, or swung downwardly to horizontal position as shown in Fig. 6. When the arms 2 are in a horizontal position, their outer ends project a distance out over the side edge of the deck A. The standards 1 are connected by a shaft 4 having an operating crank 5 or suitable turning means at one or both ends of the shaft as may be desired, and also carrying a sheave 6 adjacent to each standard. A cable 7 winds on each sheave 6 and extends upwardly therefrom over a guide sheave 8 on the upper end of the respective standard and thence over a sheave 9 on the upper or free end of the swinging arm 2. The cable at its free end carries a hook 10 for engaging in a socket 11 provided on the boat at each end thereof. The hook 10 has a substantially flat hook portion to adapt it to be easily engaged in or released from a socket 11, and at the upper end of its shank is provided with a cross-arm 12 adapted to engage with the laterally spaced hook fingers 13 at the outer or under side 25 of the free end portion of the arm 2, as hereinafter more fully described.

When it is desired to raise a boat from the water the arms 2 are lowered and the hooks 10 engaged with the boat sockets 11, after which 30 the shaft 4 is turned to effect a winding of the cables 7 on the sheaves 6. When the boat has been raised sufficiently for the cross-arms 12 of the hooks to engage the laterally spaced portions 14 at the free ends of the arms 2, the arms will 35 be caused to raise with the hooks as the raising of the boat continues until the arms are in the upright position shown in Fig. 5 with the boat B swung inwardly over the boat deck A in position to be clamped thereto. As the arms 2 swing upwardly from their horizontal positions, the cross-arms of the hooks 10 slide inwardly along the surfaces 14 and finally rest in the hooks 13, as shown in Fig. 5, thus providing a rigid support for the hooks independently of the cables 7 to hold the boat B in suspended position except for its engagement with the clamping means, which latter constitutes the principal part of the present invention and will now be described.

Rising from the deck A substantially centrally 50 of the davit standards 1 and at the inner side of the life boat B is a standard 20 having at its rear side a part 21 forming, in the present instance, a hollow housing. The standard 20 is provided at the outer side of its upper end with a boss or thrust head 22 adapted to have inter-

engaging connection with a side plate 23 on the adjacent gunwale portion of the boat A so that when the boat is swung over into mounting position on the deck, the parts 22 and 23 will interengage to prevent endwise movement of the boat relative to the standard. In the present instance, the boss 22 has a vertical recess 24 in its face and the companion plate 23 has a rib 25 on its face, which latter fits in the recess 24.

A locking hasp 26 of lever form is pivoted between the sides of the upper end portion of the hollow part 21 and has a long arm projecting outwardly so as to be swung down over the upper end of the standard 20 and the adjacent gunwale edge of the boat. The hasp 26 has its free end angled downwardly to engage the inner side of the gunwale when the parts are in assembled locking position and such angled end carries a screw bolt 27 adapted to have its inner end projected into a registering socket 28 in the gunwale and thus prevent any accidental disengagement of the hasp therefrom. In the present instance, the angled end of the hasp 26 is provided with a hand wheel 29 which, when rotated on the screw 27, effects an inward or outward movement thereof.

The inner short arm of the hasp 26 has a link 30 extending downwardly therefrom into the hollow of the part 21 and connected to one arm of a bell crank lever 31, which is pivoted within said part at the forward side thereof. The other arm of this lever projects downwardly and has a rod 32 projecting forwardly therefrom beneath the boat B and over a supporting roller 33 mounted on a bracket 34 rising from the deck A at the under side of the boat when in its mounting position. The rod 32 is provided in advance of the roller 33 with a downwardly and forwardly inclined cam portion 35 terminating at its outer end in an upwardly projecting hook 36. It is thus evident that when the hasp 26 is in raised position the hook 36 will be lowered relative to the roller 33, and that when the hasp is lowered to horizontal or bolt clamping position its connection with the rod 32 will cause it to be drawn rearward so that the cam 35 will ride up on the roller 33 and cause both an upward and a rearward movement of the hook 36. As this movement takes place the hook 36 engages the outer side of the keel 37 and draws such keel into clamping coaction with the bracket 34 and at the same time the hooked end of the hasp engages the inner side of the gunwale and firmly holds the plate 23 in interengaging thrust connection with the boss 22 on the standard 20. This clamping engagement of the hasp 26 with the gunwale and of the hook 36 with the keel of the boat is shown in Fig. 3. Should the boat, when suspended from the arms 2 when in their upright positions, as shown in Fig. 5, not be in position for its keel to bear against the outer side of the bracket 34 but spaced slightly outwardly therefrom, the hook 36 has sufficient movement in side engagement with the keel to draw it over into clamping engagement with

the bracket. It is apparent that a release of the boat B from clamped position to permit it to be swung out over and down from the deck A may be easily and quickly effected by merely releasing the bolt 27 from the gunwale and then swinging the hasp 26 upward. This disengages its hooked end from the gunwale and at the same time moves the hook 36 outward and downward out of the path of movement of the keel.

I wish it understood that my invention is not limited to any specific construction arrangement or form of the parts, as it is capable of numerous modifications and changes within the spirit of the claims.

Having thus described my invention, what I claim as new and desire to secure by United States Letters Patent is:

1. The combination with a boat, of a standard rising at a side of the boat, a thrust part fixed to the gunwale of the boat adjacent to said standard, said part and standard having interengaging connection when one is resting against the other and a hasp carried by one of said part and standard and adapted to have locking engagement with the other to secure the boat in rigid relation to the standard.

2. The combination with a boat, of a standard separate from and rising at a side of the boat, a plate fixed to the gunwale of the boat adjacent to said standard, said plate and standard having interengaging parts when one is resting against the other to prevent predetermined relative movements of the boat and standard, and a hasp carried by the standard and adapted to be swung over the plate and gunwale of the boat and having a free hook end extending at the inner side of the gunwale, and means carried by the hasp for releasable locking engagement with the gunwale to retain the interengaging parts in engagement.

3. The combination with a boat, of a standard separate from and rising at a side of the boat and having a boss at its top with an edge notch therein adjacent to the boat gunwale, means forming a part of the gunwale and having a rib for engaging in said notch, and a hasp hingedly connected to the boss and operable to engage and releasably hold said means in interengaging connection with the boss.

PETER FULL.
